Primary Examiner — Cathy A MacCormac*(74) Attorney, Agent, or Firm* — Cantor Colburn LLP(57) **CLAIM**

The ornamental design for a printer, as shown and described.

DESCRIPTION

FIG. 1 is a front perspective view of a printer showing our new design;

FIG. 2 is a front view thereof;

FIG. 3 is a rear view thereof;

FIG. 4 is a left side view thereof;

FIG. 5 is right side view thereof;

FIG. 6 is a top view thereof;

FIG. 7 is a bottom view thereof;

FIG. 8 is another right side view thereof, in which the printer is installed with an environmental desk;

FIG. 9 is another front perspective view thereof, showing the printer with an environmental removable tray; and,

FIG. 10 is another front perspective view thereof, showing the printer with a different environmental removable tray.

The broken lines illustrating portions of the printer are for environmental purposes only and form no part of the claimed design.
